(57) **CLAIM**

The ornamental design for a balloon water injector, as shown and described.

DESCRIPTION

FIG. 1 is a front perspective view of a balloon water injector, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of FIG. 1, shown in an environment of use; and,

FIG. 10 is an enlarged detail view of area 10 in FIG. 2. In the drawings, the evenly-spaced broken lines in the drawings illustrate portions of the balloon water injector, which form no part of the claimed design; the additional evenly-spaced broken lines illustrate environmental subject matter only that form no part of the claimed design. The dash-dot-dash broken lines encircling the enlarged views are for annotative purposes only and form no part of the claim thereof.
